UNITED STATES PATENT OFFICE

157,589

UTILITY TRUCK OR SIMILAR ARTICLE

Joseph A. Hartenbach, Beverly Hills, Calif.

Application May 25, 1948, Serial No. 146,589

Term of patent 3½ years

(Cl. D14—3)

To all whom it may concern:

Be it known that I, Joseph A. Hartenbach, a citizen of the United States of America residing in the City of Beverly Hills, in the county of Los Angeles, State of California, have invented a new, original, and ornamental Design for Utility Truck or Similar Article, of which the following is a specification, reference being had to the accompanying drawing, forming a part thereof.

Fig. 1 is a front perspective view of a utility truck or similar article showing my new design;

Fig. 2 is a side elevational view thereof;

Fig. 3 is a top plan view thereof;

Fig. 4 is a front elevational view of the same; and

Fig. 5 is a rear elevational view of the utility truck or similar article.

I claim:

The ornamental design for a utility truck or similar article, substantially as shown.

JOSEPH A. HARTENBACH.
